UNITED STATES PATENT OFFICE.

JOHN SEYMOUR POWELL, OF MARSHALL, TEXAS.

ROPE ATTACHMENT.

SPECIFICATION forming part of Letters Patent No. 408,894, dated August 13, 1889.

Application filed April 25, 1889. Serial No. 308,522. (No model.)

To all whom it may concern:

Be it known that I, JOHN SEYMOUR POWELL, a citizen of the United States, residing at Marshall, in the county of Harrison and State of Texas, have invented certain new and useful Improvements in Rope Attachments for Snap-Hooks; and I do hereby declare the following to be a full, clear, and exact description of the invention, such as will enable others skilled in the art to which it appertains to make and use the same.

My invention relates to a novel and useful device which is adapted to be rigidly and substantially secured to the end of a rope, and which is constructed with a curved lip on its protruding end, so that when pressed over the loop of a snap-hook it will form a link or jointed connection of the snap-hook with the rope, ferrule, or clamp, as will be fully understood from the following description and claim, taken in connection with the annexed drawings, in which—

Figure 1 is a perspective view of one end of a rope, showing my improved ferrule compressed thereon, the transverse lip of this ferrule being clinched. This figure also shows one of the well-known snap-hooks as it would appear if detached from the eye of the ferrule. Fig. 2 is a longitudinal central section of the ferrule before it is compressed on the end of a rope, and Fig. 3 is a top view of the device.

Similar letters of reference indicate corresponding parts in the three figures.

Before describing my invention I desire to state that I am aware that it is not new to construct a snap-hook with an elongated shank having lateral lips and teats for the purpose of compressing the shank-lips and teats into and about a rope, the said shank, the hook, the side lips, and the teats being cast integral. Therefore I disclaim such a device.

My object is to form of malleable metal a ferrule having a broad transverse lip, together with the lips and teats, the said lip being adapted to receive the loop of any well-known or improved snap-hook, and when it (the lip) is compressed will form a broad hinge joint between the ferrule and the snap-

hook and allow a free articulation at the point of union.

Referring to the annexed drawings, A designates a common rope, which may be made of hemp, wire, or of any other suitable material. One end of this rope is cut off short, and about this end I apply my improved ferrule, shield, or guard B, which I prefer to make of malleable iron, although it may be made of any other suitable metal.

I represent in the annexed drawings a ferrule having a body a, lips b, teats or tapered bosses, spurs, or lugs c c, and a broad front extension E, which, with the said parts a, b, and c, are cast or formed integral. The said extension E is designed, when pressed into the form shown in Figs. 2 and 3, to receive the straight pintle portion d' of a snap-hook C, and when this portion is adjusted into place, as stated, and the lip is compressed as shown at d, Fig. 1, it forms a broad transverse eye or hinging portion for the snap-hook. I thus compress and close the ends of the strands of a rope, firmly unite an eye to the rope, and adapt a rope-ferrule to have pivotally attached to it any well-known snap-hook.

I am aware that Letters Patent No. 59,890, dated November 20, 1866, shows a rope attachment for a snap-hook, formed of a single piece of metal having a cylindrical shank provided with spurs, and a tapered hook, round in cross-section, on one end. Such a device I broadly disclaim.

The essential feature of my invention consists, first, in a body having thin laterally-tapered scalloped edges forming lips b; second, in a hooked extension, which is fully as broad as the body B when this body is compressed and flattened upon a rope, the thin rounded lips b embedding themselves into the rope strands, and thus materially aiding in holding the attachment upon the rope; third, in adapting the extension E to receive the elongated bar d' of a snap-hook and to be compressed upon such bar, so as to form a long hinge-joint, which will prevent any lateral shackle movement of the snap-hook.

What I claim as new, and desire to secure by Letters Patent, is—

The within-described improved article of manufacture, consisting of a rope attachment having an elliptical body or ferrule B, provided with thin rounded lips b, a thick base 5 having spurs c c, a broad laterally-extended eye on one end, and a snap-hook having its elongated bar d' held in said eye, forming a broad hinge-joint, as specified.

In testimony whereof I affix my signature in presence of two witnesses.

JOHN SEYMOUR POWELL.

Witnesses:

C. A. DYKE,
JNO. D. HEARD.
